UNITED STATES PATENT OFFICE.

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING-LOOM BOBBIN CLEANER.

Application filed April 22, 1927. Serial No. 185,725.

This invention relates to filling replenishing looms and more particularly to bobbin cleaning attachments applied to such looms for removing the waste filling from filling carriers or bobbins as they are successively ejected from the shuttle.

In that type of filling replenishing looms wherein the bobbin is ejected from the shuttle on replenishment and a fresh one inserted, an amount of waste filling remains on the filling carrier or bobbin which must be removed before the filling carrier or bobbin can be rewound with filling. It is important, therefore, that the bobbin cleaning attachment shall be so contrived as to insure that all of the successive bobbins as they are ejected from the shuttle shall have the filling removed therefrom before they are permitted to pass from the attachment.

20 In attachments of this sort as heretofore constructed, the incoming filling carrier ejected from the shuttle is liable at times to be discharged from the cleaning attachment without being cleaned, a condition which necessitates hand manipulation of the bobbins to separate the cleaned from the uncleaned bobbins and the removal of waste from the uncleaned ones.

30 An important feature of the present invention, therefore, consists in providing a filling replenishing loom with a bobbin cleaning attachment which will insure that each incoming filling carrier shall be cleaned of its waste yarn or filling before it is discharged from the cleaning attachment.

35 The invention and novel features thereof and new combination of parts will best be made clear from the following description and the accompanying drawings of one good form thereof.

40 In the drawings:

Fig. 1 is a perspective view of the replenishing side of the loom with some of the parts broken away, and having the present invention associated therewith;

45 Fig. 2 is a section through the bobbin cleaning attachment showing the bobbin in cleaning position; and

50 Fig. 3 is a similar section showing the cleaned bobbin as being discharged from the cleaning attachment and the incoming bobbin as it is ejected from the shuttle.

In accordance with the present invention, a cleaning and an idle roll are normally held

in close relation to support upon them the 55 filling carrier to be cleaned, and on replenishment of filling the cleaned filling carrier is discharged by relative movement of the two rolls which are returned to their bobbin supporting positions before the completion of the filling replenishing operation. 60

In the drawings, the loom frame 1 is, or may be, of usual construction, and on the breast beam 2 is mounted the hopper stand 3 which is shown as having a stud shaft 4 65 on which is mounted the rotary hopper 5 containing a series of filling carriers or bobbins 6 which are successively moved to replenishing position.

Extending from the hopper stand is the 70 stud or dead shaft 7 on which is mounted the transerrer 8 having an arm 9 connected with a dog 10 which, on call for replenishment of filling, is positioned to be struck by a bunter on the lay to effect replenishment. This mechanism is, or may be, of usual type, and, being well understood in the art, requires no further description.

Secured to the loom frame is a bracket 11 having a rim portion 12 on which is supported the bobbin receiver 13 for receiving the ejected filling carriers or bobbins as they are delivered from the shuttle on replenishment of filling.

Extending transversely of the bobbin receiver 13 is a bobbin cleaner shaft 14 on which is mounted for rotary movement the bobbin cleaner 15 having a roughened surface which in the present instance is shown as a series of teeth 16. The shaft 14, Fig. 90 1, is extended beyond the side of the bobbin receiver 13 and has a bearing 17 which may be appropriately supported by a bracket 18 secured to the loom frame. The shaft 14 is provided with a belt pulley 19 driven by a belt 20 from a going part of the loom, such, for instance, as the cam shaft 21, on which is mounted the belt pulley 22, the construction being such that during the loom operation, the bobbin cleaner 15 will 95 be rotated.

Cooperating with the bobbin cleaner 15 is an idle roll 23, and the cleaning roll and idle roll are normally in close relation or contact, it may be, to support a bobbin *a*, Fig. 2, between the two rolls, in bobbin cleaning position, so that the end of filling on the bobbin may engage the teeth of the

bobbin cleaner and be unwound from the bobbin.

The two rolls 15 and 23 are mounted for movement towards and from each other during replenishment of filling, for the purpose of discharging a cleaned bobbin between them, and immediately thereafter to return to initial bobbin cleaning position.

It is important that the incoming bobbin to be cleaned shall not pass between the two rolls before it is cleaned, and an important feature of the present invention therefore consists in means for separating the rolls for the discharge of the cleaned bobbin, and immediately thereafter and prior to the completion of the replenishing operation, to cause said rolls to return to their initial bobbin cleaning position, so that the incoming filling carrier to be cleaned will be caught by the rolls and not be permitted to pass from the bobbin cleaner without being cleaned.

As shown in the present instance of the invention, the idle roll 23 is mounted upon a swinging arm 24 secured to the shaft 25 mounted in the bobbin receiver, and if desired a light spring 26 may be employed for normally holding the arm 24 with the idle roll 23 in close proximity to or in contact with the bobbin cleaner, as indicated in Fig. 2.

The shaft 25 has extending upwardly therefrom the arm 27 connected by a link 28 to an actuator 29. The actuator 29 is shown as pivotally supported at 30 on the outside of the bobbin receiver and its downwardly extending arm is connected to the link 28 at 31. Extending laterally from the pivotal support 30 is the arm 32, the end portion of which has an inclined surface 33 which may be formed as shown by a hook member 34.

The transverse or change shaft 35 which, as usual, is mounted at the front of the loom for rocking movement in the bearings 36, has extending downwardly therefrom the arm 37, to the lower end portion of which is secured a carrier 38 for a one-way trip device. As shown in the present instance of the invention, the one-way trip device comprises a pivoted member 39, pivoted at 40 to the carrier 38, and has a trip or inclined surface 41 adapted to engage the end of the arm 32 of the actuator, and extending upwardly from the pivotal point 40 the one-way trip has a stop member 42 which normally rests against a stop 43 when the parts are in normal position, as indicated in Fig. 2, and during the intervals between replenishment of filling. The construction is such that on rocking movement of the transverse or change shaft and backward movement of the arm 37, the one-way trip device 39 will engage the end of the arm 32 and cause the actuator 29 to be

moved upon its pivotal support 30 to separate the idle roll 23 from the cleaning roll 15 for the discharge of a cleaned bobbin, and immediately thereafter the trip device 39 will pass beyond the end of the arm 32, thereby freeing the actuator, so that the cleaning and idle rolls are returned to their initial position before replenishment of filling is completed.

Pivots supported at 44 is the bobbin catcher 45, the lower end portion 46 of which is normally adjacent to the upper portion of the idle roll 23, and extending from the end 46 of the bobbin catcher is the arm 47. When the parts are in normal position during the weaving operation, they are as shown in Fig. 2, but when the idle roll 23 is separated from the cleaning roll 15, as hereinbefore described, the idle roll will engage the lower end of the bobbin catcher and move along the arm 47 which inclines from the main portion of the bobbin catcher, to thereby lift the bobbin catcher in an upward direction, in the present instance, so that an incoming filling carrier or bobbin to be cleaned may be caught by the bobbin catcher when the cleaning roll moves back to its initial position, and direct the bobbin to be cleaned into cleaning position. The bobbin catcher 45 may be provided with a stop member 48, whereby it will be normally supported in the position indicated in Fig. 2, but with permissive upward movement, by the idle roll.

When the ejected filling carrier is received into the bobbin receiver, the ejecting impulse of the transceiver throws the incoming bobbin with considerable force, and to arrest the bobbin under such conditions without injury thereto, the bobbin receiver has at its front portion a bobbin stop 49 which may be preferably formed of canvas or other yielding material and supported at its upper end by a rod 50 and at its lower end by a rod 51 positioned preferably above the bobbin cleaner 15.

From the construction described as one good practical form of the present invention, it will be apparent that on call for replenishment of filling and rocking movement of the transverse or change shaft 25, the one-way trip device 39 will engage the end portion of the arm 32 of the actuator and swing the actuator to move the idle roll 23 away from the bobbin cleaner, to permit the cleaned bobbin to pass between the two rolls. The one-way trip 39 will continue its movement and trip past the end portion 34 of the arm 32, thereby freeing the actuator, and permit the idle roll 23 to return to its initial bobbin supporting position, as indicated in Fig. 2, and prior to the completion of the filling replenishing operation, so that the incoming filling carrier cannot be discharged from the bobbin cleaner until after it has been cleaned.

On the return movement of the one-way trip device 39, it is freed to swing past the end 34 by pivotal movement upon its support 40. When the idle roll 23 is separated from 5 the cleaning roll on call for replenishment of filling, as indicated in Fig. 3, it will engage the arm 47 of the bobbin catcher, thereby lifting it into bobbin arresting position so that the incoming bobbin may strike 10 the stop 49 and then fall towards the bobbin catcher. The idle roll 23 having moved to its bobbin cleaning position, as indicated in Fig. 2, and prior to the arrival of the incoming filling carrier, the bobbin catcher 45, 15 which is inclined, will direct the incoming bobbin into bobbin cleaning position.

When the cleaned bobbin is discharged from the cleaning position, as indicated in Fig. 3, it passes through the open bottom 20 52 of the bobbin receiver into the bobbin can 53 beneath, and when an accumulation of bobbins has been made in the bobbin can they may be taken to the winding machine.

What is claimed is:

25 1. In a filling replenishing loom, the combination of replenishing mechanism, a bobbin receiver having a rotary bobbin cleaner roll, an idle roll normally resting in close relation to the cleaner roll and in cooperation therewith to support a bobbin by both 30 rolls while being cleaned, and means actuated on replenishment of filling for relatively separating the two rolls to discharge a cleaned bobbin and permit relative movement of said rolls to initial position to support an incoming bobbin to be cleaned.

40 2. In a filling replenishing loom, the combination of replenishing mechanism, a bobbin receiver having a rotary bobbin cleaner roll, an idle roll normally resting in close relation to the cleaner roll and in co-operation therewith to support a bobbin by both rolls while being cleaned, means actuated on replenishment of filling for relatively separating the two rolls to discharge a cleaned bobbin and permit relative movement of said rolls to initial position to support an incoming bobbin to be cleaned, and an incoming bobbin catcher which is moved to bobbin 45 catching position as the rolls are separated.

50 3. In a filling replenishing loom, the combination of replenishing mechanism, a bobbin receiver, a rotary bobbin cleaner roll, an idle roll normally resting in close relation to the cleaning roll to support a bobbin above the rolls for cleaning purposes, and means actuated on replenishment of filling for moving the idle roll away from the cleaning roll to discharge a cleaned bobbin.

60 4. In a filling replenishing loom, the combination of replenishing mechanism, a bobbin receiver, a rotary bobbin cleaner roll, an idle roll normally resting in close relation to the cleaning roll to support a bobbin above the rolls for cleaning purposes, and means

including a one-way trip actuated on replenishment of filling for separating the two rolls to discharge a cleaned bobbin and permit said rolls to move to bobbin cleaning position prior to completion of the replenishing operation. 70

5. A bobbin cleaner comprising, in combination, a bobbin receiver, a rotary bobbin cleaning roll, an idle roll normally resting in close relation to the cleaning roll that a bobbin to be cleaned may rest upon and be supported by both of said rolls while being cleaned, and means actuated on replenishment of filling for separating said rolls during the replenishing intervals to permit the cleaned bobbin to pass between said rolls. 75

6. In a filling replenishing loom, the combination of replenishing mechanism, a bobbin receiver, a rotary bobbin cleaner roll, an idle roll normally resting in close relation to the cleaning roll that a bobbin to be cleaned may be supported by both of said rolls, an arm carrying one of said rolls, and means actuated on replenishment of filling for moving said arm to separate the rolls 90 that a cleaned bobbin may pass between them and then to permit said arm to relatively move the rolls into close relation before the incoming bobbin reaches bobbin cleaning 95 position.

7. In a filling replenishing loom, the combination of replenishing mechanism, a bobbin receiver, a rotary bobbin cleaner roll, an idle roll normally resting in close relation to the cleaning roll that a bobbin to be cleaned may be supported by both of said rolls, an arm carrying one of said rolls, means actuated on replenishment of filling for moving said arm to separate the rolls 100 that a cleaned bobbin may pass between them and then to permit said arm to relatively move the rolls into close relation before the incoming bobbin reaches bobbin cleaning position, and an incoming bobbin catch which is moved by one of said rolls as they 105 are separated to arrest an incoming bobbin. 110

8. In a filling replenishing loom, the combination of replenishing mechanism, a bobbin receiver, a rotary bobbin cleaning roll, an idle roll normally resting in close relation to the cleaning roll to support a bobbin to be cleaned, means for supporting one of said rolls for movement towards and from the other roll, an arm having a one-way trip actuated on movement of the arm in one direction during replenishment of filling to separate the rolls for the discharge of a cleaned bobbin and then permit the rolls to move into close relation before the incoming 115 bobbin reaches bobbin cleaning position. 120

9. In a filling replenishing loom, the combination of replenishing mechanism, a bobbin receiver, a rotary bobbin cleaning roll, an idle roll normally resting in close relation to the cleaning roll to support a bobbin to 125 130

- be cleaned, means for supporting one of said rolls for movement towards and from the other roll, an arm having a one-way trip actuated on movement of the arm in one direction during replenishment of filling to separate the rolls for the discharge of a cleaned bobbin and then permit the rolls to move into close relation before the incoming bobbin reaches bobbin cleaning position, and a bobbin arrester which is moved into bobbin arresting position as the rolls are separated and then back to initial position to discharge an incoming bobbin onto the two rolls.
- 10 15. In a filling replenishing loom, the combination of a bobbin receiver, a rotary bobbin cleaning roll mounted therein, an idle
- roll, a supporting member normally supporting the idle roll in close relation to the cleaning roll, an actuator connected to the supporting member for moving the idle roll away from the cleaning roll to cause discharge of a cleaned bobbin, the transverse or change shaft having an arm extending therefrom, a trip pivotally mounted on said arm for engagement with the actuator to separate the idle roll from the cleaning roll on replenishment of filling and then to release the actuator prior to completion of the replenishing operation.

In testimony whereof, I have signed my name to this specification.

WALLACE I. STIMPSON.
